UNITED STATES PATENT OFFICE

THOMAS WAUGH, OF LOWELL, MASSACHUSETTS

HEEL PROTECTOR FOR SHOES

Application filed January 21, 1931. Serial No. 510,144.

This invention relates to a heel protector which is designed to be placed inside of the shoe at the heel portion thereof and has for its function to protect the heel of the stocking 5 from becoming worn by the slippage which frequently occurs between the heel and the lining of the shoe.

My improved heel protector comprises a friction member in the form of a flap that is 10 secured at its upper edge to the upper edge of the heel of the shoe at the counter but is free from the shoe except at the upper edge, and one or more layers having a more or less slippery surface located between the friction 15 flap and the lining of the shoe.

The friction flap which is free from the shoe except at the top edge will have sufficient frictional engagement with the heel portion of the sock so that it will tend to cling 20 to the sock and as the heel slides up and down in the shoe during the operation of walking the slippage will occur between the friction flap and the heel of the shoe due to the presence of the layers having the more or less slippery surface which are situated between said 25 flap and the shoe. There will, therefore, be no chafing of the sock and all wear incident to slipping of the sock will be avoided.

In order to give an understanding of the 30 invention I have illustrated in the drawings a selected embodiment thereof which will now be described after which the novel features will be pointed out in the appended claims.

In the drawings:

35 Fig. 1 is a fragmentary perspective view of a shoe having my improvements therein.

Fig. 2 is another fragmentary view illustrating my improved sock protector and showing part of the protector broken out to better 40 illustrate the construction.

Fig. 3 is a section on the line 3—3 of Fig. 2.

Fig. 4 is a view similar to Fig. 3 illustrating the manner in which my device operates to protect the sock.

45 In the drawings 1 indicates a portion of a shoe of ordinary construction.

My improvements consist of a friction flap member 2 which is located inside of the heel portion of the shoe and is free from the shoe 50 except at the upper edge 3 where it is attached

to the shoe by cement or staples or any other suitable fastening.

Situated between this flap and the interior of the shoe are one or more layers of material which have a more or less slippery surface. Celluloid makes an excellent material for this purpose. In this construction there are two of these celluloid layers indicated at 55 5 and 6 respectively. The layer 5 is shown as adhesively secured to the inside of the flap 2 and the layer 6 is suspended from its upper edge but is otherwise free from both the shoe 60 and the flap 2.

Any suitable way of suspending the layer 65 6 may be employed. As herein shown said layer has a thread or cord 7 attached to its upper end and this thread or cord is either secured to the top edge of the flap 2 or is retained in position by having its upper end confined between the flap and the shoe at the 70 point where the flap is adhesively united to the shoe. If desired, I may employ a padding layer 9 which is introduced between the celluloid strip 5 and the member 2, this pad being for the purpose of providing a 75 cushion effect. Where the pad is employed it will be adhesively united both to the flap 2 and the celluloid layer 5.

The pad 2 may be perforated as shown 80 at 10 in order to increase the frictional engagement between the flap and the shoe and if desired the pad 9 may have an opening 11 therein which will tend to form a slight recess in the member 2 thereby to further increase the frictional engagement between 85 said member and the sock.

When the device is used the frictional engagement between the member 2 and the sock will cause the member to adhere to the heel 90 of the sock sufficiently so that it will move up and down with the heel of the person wearing the shoe and, therefore, any slipping movement which occurs will take place between the celluloid layers 5 and 6. The sock will thus be subjected to no wear and if the layers 95 5 and 6 are made of celluloid or some other similar material they will not be affected by any wear which comes from a slipping motion between them.

The device can be inexpensively manufac- 100

tured and can be easily attached to the shoe by anyone.

I claim:

1. The combination with a shoe, of a friction flap member located on the inside of the heel of the shoe and attached thereto at the upper edge of the shoe only, said flap being otherwise free from the shoe, and a plurality of plies of thin flexible but somewhat slippery material located between the flap and the shoe.

2. The combination with a shoe, of a friction flap member located on the inside of the heel of the shoe and attached thereto at the upper edge of the shoe only, said flap being otherwise free from the shoe, and a plurality of plies of thin flexible but somewhat slippery material located between the flap and the shoe, one of said plies being adhesively united to the flap and the other being attached at its upper edge of the shoe but otherwise free therefrom.

In testimony whereof, I have signed my name to this specification.

25 THOMAS WAUGH.
